UNITED STATES PATENT OFFICE.

JOHN J. TATUM, OF BALTIMORE, MARYLAND.

AUTOMATIC DOOR-LATCH.

935,946.

Specification of Letters Patent.

Patented Oct. 5, 1909.

Application filed September 11, 1906. Serial No. 334,153.

To all whom it may concern:

Be it known that I, JOHN J. TATUM, of Baltimore, Maryland, have invented a new and useful Improvement in Automatic Door-
5 Latches, which improvement is fully set forth in the following specification.

The present invention is an improvement in fasteners for sliding doors, such as those used on freight cars, and has for its object 10 to provide a simple and economical device of this character which is automatic in action and which will effectively secure and retain the door in its closed position when the same is either purposely or accidentally 15 forced against the door stop; and to provide means for not only thus holding the door in its closed position, but to readily seal the same in its locked position.

A further object is to prevent the door 20 from being opened without breaking the lock or seal.

The invention will be more thoroughly comprehended by an inspection of the accompanying drawings, wherein—

25 Figure 1 is a perspective view of a freight car showing the application of the improved lock; Fig. 2 is a transverse sectional view; Fig. 3 is a view in elevation; Fig. 4 is a vertical section through the lock; and Fig. 5 is 30 a view in elevation at right angles to Fig. 3.

Referring to the drawings, 1 is a sliding door, for instance the door of a freight car, and 2 is a door stop, here shown as Z-shaped in cross-section, suitably secured to the wall 35 of the structure or car as by bolts 2', and against which stop the door rests when in its closed position. A U-shaped keeper 3 which binds the front edge of the door at the point where it engages the locking latch, is 40 fastened to the door by suitable securing means 4, and is provided with an opening 5 into which extends a projection 6, which is here shown as integrally formed with the keeper. Suitably secured to the door stop 2 45 is a plate 7 provided with lugs or ears 8 between which is pivotally mounted a latch 9 which is inclined at its forward end and provided with a cut-out portion 10 in which the projection 6 is adapted to engage and be 50 retained to hold the door in its closed position. Plate 7 is also provided with a lug 11. Pivots secured to the rear end of the latch 55 is a locking bar 12, the weight of which tends to force the locking end of the latch into an elevated position. This bar is provided with ears or lugs 13 having perfora-

tions 14 formed therein, and between which lugs 12 is provided an opening 12', so that said lug 11, when the bar 12 is in the position illustrated in Fig. 1, passes through opening 12' and the perforations in the lugs 13 will be in alinement with a similar perforation in lug 11; and a seal or lock 15 may readily be passed through the alined openings, thus securing all the parts in their locked position. Plate 7 is further provided with a lug 16 extending through the keeper and above projection 6, the function of which is to prevent the door from being raised so that the projection 6 might be removed from the cut-out portion 10 to permit the car door being moved back, and rendering the contents of the car accessible without breaking the seal. Although the lugs 11 are herein shown as attached to plate 7 which latter is secured to the door stop 2, it will of course be understood that plate 7 may be omitted and the elements indicated formed integrally or otherwise with or on the door stop itself.

The operation of the device is as follows: When the door is open, the forward end of latch 9 occupies an elevated position by reason of the weight of locking bar 12, which latter swings clear of lug 11 so that the latter 55 cannot pass through opening 12'. Should now the door be either accidentally or otherwise forced against the door stop, projection 6 by engaging with the incline of the latch causes the forward end thereof to be depressed until the said projection engages in the cut-out portion 10 when the weighted rear end of the latch will hold said projection and cut-out portion in intimate engagement. When the latch 9 has thus engaged 95 the projection 6, the locking arm is in a position to permit lug 11 to pass through opening 12', and said locking arm may readily be forced into contact with plate 7 and a seal or lock 15 passed through the alined openings 100 in lugs 11 and 13.

The fact that when the door is open latch 9 is so swung on its pivot that the opening 12' in locking arm 12 is out of register with lug 11, prevents said lug from accidentally engaging with said opening to hold the latch in its locked position when the door is open, the result of which would be serious damage to the latch if the door was forced against the same when it could not 110 swing on its pivot.

To open the door it is only necessary to

swing locking arm 12 on its pivot to remove lug 11 from opening 12', then rock latch 9 to disengage projection 6 from cut-out portion 10, when the door will be free to be 5 opened.

It will thus be seen that the present invention provides a simple and efficient closing device which may be very rapidly locked by a trainman, and which when locked pre- 10 cludes access being had to the car except by breaking the lock or seal.

What is claimed is:

1. In a fastener for sliding doors, the combination of a pivoted latch normally held in 15 latching position, a projection adapted to engage said latch to retain the door in closed position, and a depending element pivoted to said latch for maintaining the same in latching position.
2. In a fastener for sliding doors, the combination of a pivoted latch normally held in latching position, a projection adapted to engage said latch to retain the door in closed 20 position, and a combined weight and locking member depending from said latch for hold- 25

ing the same in latching position and effecting the locking thereof.

3. In a fastener for sliding doors, the combination of a pivoted latch, a projection adapted to engage said latch to retain the 30 door in its closed position, and gravity-actuated automatic means associated with said latch for normally holding its engaging end in a horizontal plane above its pivot and for effecting the latching of the same.

4. In a fastener for sliding doors, the combination of a pivoted latch, a projection adapted to engage said latch to retain the door in its closed position, and a combined weight and locking member depending from 40 said latch for normally holding its engaging end in a horizontal plane above its pivot and for effecting the latching of the same.

In testimony whereof I have signed this specification in the presence of two sub- 45 scribing witnesses.

JOHN J. TATUM.
